[57] CLAIM

The ornamental design for a vertical file module, as shown and described.

DESCRIPTION

FIG. 1 is a front elevational view of a vertical file module showing my new design, the rear elevational view being a mirror image of this view;

FIG. 2 is a side elevational view of the right side thereof;

FIG. 3 is a side elevational view of the left side thereof;

FIG. 4 is a top plan view thereof;

FIG. 5 is a bottom plan view thereof; and

FIG. 6 is a perspective view thereof on an enlarged scale.

FIG. 1

FIG. 2

FIG. 3

FIG. 4

FIG. 5

FIG. 6
